(57) CLAIM

We claim the ornamental design for a sports table, as shown and described.

DESCRIPTION

FIG. 1 is a perspective view of the claimed design;

FIG. 2 is a front elevation of the claimed design;

FIG. 3 is a top elevation of the claimed design; and,

FIG. 4 is a bottom elevation of the claimed design.

The ornamental design which is claimed is shown in solid lines in the drawings. The broken lines in the drawings are for illustrative purposes only and form no part of the claimed design
